CAN PUNCTURING APPARATUS

Clyde R. Hopper, Norman, Okla.
(15629 S. Harris Ave., Compton, Calif.)

Filed July 10, 1959, Ser. No. 826,195

5 Claims. (Cl. 30—4)

The present invention relates to an apparatus for puncturing the top of a can such as a beer can.

Previously proposed and presently in use are beer can puncturing devices in various forms. Some of the devices proposed are hand actable and comprise knives connected to levers and the levers pivotally mounted upon suitable supports adapted for securement to a bench, bar, back-bar, or the like. Other devices proposed employ electric drive means for operating the knives which are intended to puncture the can top and which devices are enclosed in housings suitable for mounting upon a bar, bench, or back-bar. Such devices which have been proposed and are in use have not met with commercial success for many reasons, principally, that each of such devices proposed has been expensive to fabricate and install. Other devices proposed have failed for reasons of lack of sufficient safety afforded the operator thereof, multiplicity of parts difficult to fabricate and assemble, and inaccessibility of the cutting elements which puncture the can when replacement is deemed necessary.

An object of the present invention is to provide a can puncturing apparatus which affords the operator thereof complete safety when puncturing a can, one in which the cutting or puncturing elements are readily accessible to an operator for replacement when necessary, one having a positive drive action, and one highly effective in action.

Another object of the present invention is to provide a can puncturing apparatus which is sturdy in construction, one economical to manufacture and assemble, one having relatively few parts readily replaceable when worn, and one which is automatic in operation.

These and other objects and advantages of the present invention will be fully apparent from the following description when taken in conjunction with the annexed drawings, in which:

Figure 1 is an isometric view of the can puncturing apparatus of the present invention;

Figure 2 is an elevational view, viewed from the front of the apparatus shown in Figure 1 with the cover removed;

Figure 3 is a plan view, with the cover removed;

Figure 4 is a side elevational view with the cover removed, a portion of the frame of the apparatus being shown broken away; and

Figure 5 is a fragmentary side elevational view partially in section, as viewed from the other side with respect to Figure 4.

Referring in greater detail to the drawings in which like numerals indicate like parts throughout the several views, the can puncturing apparatus of the present invention is designated generally by the reference numeral 10 and comprises an upstanding housing 12 in the form of an open bottom cover having a portion of its front wall 14 provided with an opening 16.

The apparatus 10 includes a platform 18 extending inwardly from the open front wall 14 of the housing 12, the platform 18 being of a size to support an upstanding

2

can thereon, such a can being shown in dotted lines in Figure 3 and designated by the numeral 20.

The apparatus 10 includes a block or base 22, the upper surface of which forms the platform 18, and above which rises a skeleton frame 24 including a pair of opposed side edge angle iron frame members 26 and 28 secured by conventional fastening elements such as screws 30 to the base 22.

Rising from the forward end of the frame members 26 and 28 are uprights 32 and 34, each fabricated of angle iron or the like. Rising from the rearward end of the frame members 26 and 28 are other uprights 36 and 38, as shown most clearly in Figure 3.

The upper ends of the uprights 32 and 36 are connected together by an angle iron top piece 40, and the upper ends of the other uprights 34 and 38 are connected by a second angle iron top piece 42.

Extending between the uprights 32 and 36 are horizontally disposed side pieces 44 and 46, each formed of angle iron, disposed so that their horizontal legs are spaced from each other and their vertical legs are in abutting edge to edge relation. Other side pieces 48 and 50 are similarly disposed between the uprights 34 and 38 and are in lateral spaced relation with respect to the side pieces 44 and 46, intermediate the ends of the uprights 32, 34, 36, and 38.

Front and rear horizontal angle iron pieces 52 and 54 extend between the side pieces 44 and 48 and have their horizontal legs supported on the horizontal legs of such side pieces 44 and 48.

An overhead floating plate 56 is positioned between the pieces 52 and 54 and has its ends within the channels formed by the vertical flanges of the side pieces 44 and 48, and 46 and 50.

Four bolts 58 extend through the horizontal flanges of the side pieces 44 and 48, and 46, 50, and through holes provided in the side edge portions of the floating plate 56. The bolts 58 connect the floating plate 56 to the frame 24 for upward and downward movement.

Puncturing elements 60 and 62 are arranged in spaced relation and depend from the underface of the floating plate 56, each of the elements 60 and 62 having a threaded upper end portion threaded in a bore provided in the floating plate 56 with a suitable lock nut 64 securing each of the elements 60 and 62 to the floating plate 56.

Supported intermediate the ends of the angle iron pieces 52 and 54 are bearing blocks 66 and 68, respectively, in which are journaled the end portions of a drive shaft 70.

The shaft 70 has an intermediate portion bent to form crank throws 72 and 74 and a crank 76 connecting the free ends of the throws 72 and 74 together. A roller 78 is mounted upon the crank 76 for free rotation thereabout.

The crank 76 constitutes a member adjacent the shaft 70 and connected to the shaft 70 for rotation with the latter.

The roller 78 constitutes means connecting the floating plate 56 to the crank 76 so that the floating plate 56 moves upwardly and downwardly with respect to the platform 18 responsive to rotary movement of the shaft 70.

A combined motor and speed reduction unit, designated generally by the numeral 80, is positioned between and rearwardly of the uprights 34 and 38 above the platform 18 and is fixedly secured to transverse angle iron members 82. The output shaft 84 of the unit 80 is connected by a flexible coupling 86 to the portion of the shaft 70 adjacent the bearing block 68, as shown most clearly in Figure 4.

A semicylindrical partition 88 is positioned inwardly of the opening 16 in the housing front wall 14 and has

its lower end resting upon the platform 18. The partition 88 is formed with a slot 90 through which projects a portion adjacent one end of a resilient switch actuating element 92. The other end of the element 92 is pivotally connected within a microswitch 94 which is normally in off position and is shifted to on position when the element 92 is moved rearwardly through the slot 90 in response to pressure thereon of the wall of a can to be opened.

Wires 96 connect the microswitch 94 to a common switch 98 which has operating buttons 100 exteriorly of the frame 24 and accessible to a user of the apparatus 10 when the housing 12 is removed from the frame 24.

In use, the electric supply cord 102 is plugged into a conventional electrical outlet box and the apparatus 10 is supported in a convenient place accessible to an individual having cans to open, such as a bartender or the like. Upon insertion of a can to be opened in the housing opening 16 and into abutting engagement with the projecting end portion of the element 92, the microswitch 94 is shifted to closed condition, energizing the motor of the unit 30 and effecting the rotation of the shaft 70 so that the roller 78 travels downwardly and into engagement with the upper face of the floating plate 56. This causes the floating plate 56 to move downwardly and to project the pointed lower end portion of the blade elements 60 and 62 simultaneously through the top of the can 20 when the later is positioned on the platform 18. As the shaft 70 continues to rotate, the crank 76 is carried upwardly so that the roller 78 no longer engages the floating plate 56 and the floating plate is returned to its upward movement position under the action of springs 104 which have their upper ends hooked in the top pieces 40 and 42 and their lower ends hooked in the adjacent parts of the floating plate 56.

Upon removal of the punctured can 20 from the platform 18, the switch 94 returns to open position deenergizing the motor the unit 30 and bringing the shaft 70 to a stop with the roller above the shaft 70 and out of engagement with the floating plate 56.

What is claimed is:

1. In a can puncturing apparatus, a platform adapted to support an upstanding can to be punctured, an overhead floating plate, at least two puncturing elements arranged in spaced relation and dependingly carried by said floating plate, a drive shaft, a member embodying a crank adjacent said shaft and connected to said drive shaft for rotation with the latter, and means embodying a roller on said crank connecting said floating plate to said member so that said floating plate moves upwardly and downwardly with respect to said platform responsive to rotary movement of said crank.

2. In a can puncturing apparatus, a platform adapted to support an upstanding can to be punctured, an overhead floating plate, at least two puncturing elements arranged in spaced relation and dependingly carried by said floating plate, a drive shaft, a member adjacent said shaft and connected to said drive shaft for rotation with

the latter, means connecting said floating plate to said member so that said floating plate moves downwardly with respect to said platform responsive to rotary movement of said member, and spring means operatively connected to said floating plate urging the latter to its upward movement position.

3. In a can puncturing apparatus, a platform adapted to support an upstanding can to be punctured, an overhead floating plate, at least two puncturing elements arranged in spaced relation and dependingly carried by said floating plate, a drive shaft, a member embodying a crank adjacent said shaft and connected to said drive shaft for rotation with the latter, means embodying a roller on said crank connecting said floating plate to said member so that said floating plate moves downwardly with respect to said platform responsive to rotary movement of said crank, and spring means operatively connected to said floating plate urging the latter to its upward movement position.

20 4. A can puncturing apparatus comprising a platform

adapted to support an upstanding can to be punctured, a frame rising from said platform, a floating plate disposed above said platform and connected to said frame for upward and downward movement, at least two

25 puncturing elements arranged in spaced relation and dependingly carried by said floating plate, a drive shaft positioned above said floating plate, a crank carried on said shaft, a roller rotatably mounted on said crank and engageable with said floating plate so as to effect the downward movement of said floating plate responsive to rotation of said shaft, and means operatively connected to said shaft for effecting the rotation of the latter.

30 5. A can puncturing apparatus comprising a platform adapted to support an upstanding can to be punctured, a frame rising from said platform, a floating plate disposed above said platform and connected to said frame for upward and downward movement, at least two puncturing elements arranged in spaced relation and dependingly carried by said floating plate, a drive shaft positioned above said floating plate, a crank carried on said shaft, a roller rotatably mounted on said crank and engageable with said floating plate so as to effect the downward movement of said floating plate responsive to rotation of said shaft, means operatively connected to said shaft for effecting the rotation of the latter, and spring means operatively connected to said floating plate urging the latter to its upward movement position.
